INVENTOR
Francis Henry Radeleff
BY
W. C. Crandall
ATTORNEY

UNITED STATES PATENT OFFICE.

FRANCIS HENRY RADELEFF, OF WEST ALHAMBRA, CALIFORNIA.

DIRECTION-INDICATOR FOR AUTO-VEHICLES.

1,401,187.

Specification of Letters Patent. Patented Dec. 27, 1921.

Application filed June 25, 1920. Serial No. 391,539.

To all whom it may concern:

Be it known that I, FRANCIS HENRY RADELEFF, a citizen of the United States, residing at West Alhambra, in the county of Los Angeles and State of California, have invented new and useful Improvements in Direction-Indicators for Auto-Vehicles, of which the following is a specification.

My invention is an improved direction indicator for auto vehicles.

The main object of my invention is to provide a direction indicator for auto vehicles embodying three sets of semaphore arms mounted in a suitable housing, each set including a pair of arms mounted respectively on opposite sides of the vehicle to swing vertically, and independent means for operating each pair of the arms to swing them to different relative positions; one pair of arms being designed to signal "Left," another pair to signal "Right," and the third pair to signal "Stop."

Other objects will appear hereinafter.

My invention consists in the features of construction, combination of elements, and arrangement of parts hereinafter described and pointed out in the claims.

My invention is illustrated in the annexed drawing forming a part of this specification, in which:

Figure 1 is a vertical section of my direction indicator taken on line 1—1 of Fig. 2 showing the pair of arms for signaling "Left," said arms being shown in full lines 35 in their normal position, and in dotted lines in signaling position.

Fig. 2 is a horizontal section of my direction indicator taken on line 2—2 of Fig. 1.

Fig. 3 is a section on line 3—3 of Fig. 2 40 showing the arms for signaling "Right" as disposed in their signaling position.

Fig. 4 is a view in section as seen on the line 4—4 of Fig. 2 showing the arms for signaling "Stop" in their signaling position.

Fig. 5 is a detail section on line 5—5 of Fig. 2 showing the manner of illuminating the arms by electric lamps when in their signaling position, controlled by the arm operating mechanism.

An important feature of the invention resides in a means whereby on movement of the operating levers controlling each pair of arms, at corresponding distances the arms will be caused to move to various positions.

In the drawing 1 indicates a U-shaped housing formed with a horizontal member

2, and upstanding members 3 and 4, there being vertical slots 5 in the outer side wall of said arms. A series of telescoping shafts 6, 7, and 8 are journaled in the casing member 2 midway between the arms 3 and 4, which are fitted with the handles 9, 10, and 11 respectively outside said member. Shaft 6 carries fixed wheels 12 and 13 of different diameters; shaft 7 carries wheels 14 and 15 of different diameters, and shaft 8 carries wheels 16 and 17 of corresponding diameters, all of said wheels being located within the housing member 2. Pivoted signal arms 18 and 19 for indicating "Left" 70 are mounted in the housing members 3 and 4 with wheels 20 and 21 of diameters corresponding to each other and to the wheels 13, and passing around the wheels 12 and 19 and affixed thereto is a cross cable 22, 75 and passing around wheels 13 and 20 and affixed thereto is a cable 23. Depression of the "Left" lever 9 will operate through the cables 22 and 23 to swing the arm 18 through a slot 5 in the housing member 3 80 into horizontal position and the arm 22 through a slot 5 in the housing member 4 to an inclined position as shown in Fig. 1. The signal arms 24 and 25 for signalling "Right" are mounted on wheels 26 and 27 85 of corresponding diameter in the housing arms 3 and 4, and extending between the wheels 15 and 27 is a cross cable 28, and between the wheels 14 and 26 a cable 29. Depression of the "Right" lever 10 will act 90 through the cable 28 and 29 to rock the arm 25 through a slot 5 in the housing member 4 to horizontal position and the arm 24 through a slot 5 in the housing member 3 to an inclined position as shown in Fig. 3. 95

The signal arms 30 and 31 for indicating "Stop" are mounted in the housing members 3 and 4 on wheels 32 and 33 of corresponding diameter but of a diameter less than that of wheels 16 and 17, and extending between the wheels 16 and 33 is a cross cable 34 and between the wheels 17 and 32 a cable 35. On depression of the "Stop" lever 11 the arms 30 and 31 will be swung corresponding distances through two slots 5 respectively into downwardly inclined position shown in Fig. 4.

On moving the arms 9, 10, and 11 from their normal positions spring press switches 9', 10', and 11' will operate to close their 110 electrical circuits leading through lamps 36 arranged on top of the housing arms 3

and 4 above the signal arms to direct light on the arms when they are in their signaling position; the contact members being held out of their circuit closing position when the 5 handles are in their normal position as shown in Fig. 5.

Clips 39, 40, and 41 hold the handles 9, 10, and 11 and the signal arms actuated thereby in their normal non-signaling position and in such position said handles 10 hold the switches 9', 10', and 11' open breaking the circuit of lamps 26.

While I have shown and described a specific embodiment of my invention, I do not 15 limit myself to the exact details of construction shown, but may resort to such changes and modifications as occasion may require and as may come within the scope of the appended claims, without departing 20 from the spirit of my invention.

I claim:

1. In a direction indicator for auto vehicles, three pairs of signaling arms

marked respectively "Left," "Right," and "Stop," the arms of each pair being arranged respectively at the sides of the vehicle, means for swinging the "Left" arm at the left side of the vehicle horizontally and simultaneously swinging the "Left" arm at the right side of the vehicle at an 30 angle, means for swinging the "Right" arm at the right side of the vehicle horizontally and simultaneously swinging the "Right" arm at the left side of the vehicle at an angle, and means for swinging both "Stop" 35 arms downwardly at an angle.

2. In a direction indicator for vehicles, a pair of signaling arms arranged on opposite sides of the vehicle and normally disposed in parallel relation to each other, and means 40 for swinging said arms simultaneously at different speeds relative to each other whereby one of said arms will be disposed at an angle to the horizontal when the other is positioned horizontally.

FRANCIS HENRY RADELEFF.
